MOTOR TRUCK

Evan S. Prichard, La Canada, Calif., assignor to Cook Bros. Equipment Co., Los Angeles, Calif.,
a corporation of California

Application April 6, 1953, Serial No. 24,358

Term of patent 7 years

(Cl. D14—3)

To all whom it may concern:

Be it known that I, Evan S. Prichard, a citizen of the United States, residing at La Canada, in the county of Los Angeles and State of California, have invented a new, original, and ornamental Design for a Motor Truck, of which the following is a specification, reference being had to the accompanying drawing, forming a part thereof, and in which:

Fig. 1 is a perspective view of the motor truck, showing my new design.

Fig. 2 is a side elevational view disclosing the side opposite that shown in Fig. 1.

Fig. 3 is a front elevational view.

The dominant features of my design reside in the full line portion.

I claim:

The ornamental design for a motor truck, as shown and described.

EVAN S. PRICHARD.
